GAME BOARD

Lilla C. Gamble, Worcester, Mass.

Application December 5, 1952, Serial No. 22,575

Term of patent 14 years

(Cl. D34—5)

To all whom it may concern:

Be it known that Lilla C. Gamble, a citizen of the United States, residing at Worcester, in the county of Worcester and State of Massachusetts, has invented a new, original, and ornamental Design for a Game Board, of which the following is a specification, reference being had to the accompanying drawing forming a part thereof.

Fig. 1 is a plan view of a game board, showing my new design;

Fig. 2 is a view in front elevation thereof, showing the game board closed; and

Fig. 3 is a section on line 3—3 of Fig. 2.

The other side of the board from that shown in Fig. 1 is plain. The essential features of the design are shown in full lines.

I claim:

The ornamental design for a game board, as shown and described.

LILLA C. GAMBLE.
